UNITED STATES PATENT OFFICE.

JOHNSTONE H. QUINAN, OF MIAMI, AND JEPHTHA V. HARRIS, OF KEY WEST, FLORIDA.

PORABLE CABINET.

Application filed February 28, 1924. Serial No. 695,745.

To all whom it may concern:

Be it known that we, JOHNSTONE H. QUINAN and JEPHTHA Vining HARRIS, citizens of the United States, residing at 5 Miami, in the county of Dade and State of Florida, and Key West, in the county of Monroe and State of Florida, respectively, have invented certain new and useful Improvements in Portable Cabinets, of which 10 the following is a specification.

This invention relates to a portable cabinet designed primarily for use as a bath house or dressing tent for bathers, but it is to be understood that a portable cabinet in 15 accordance with this invention can be employed as a shade or sleeping tent, wind shield or shooting blind and for any other purposes for which it is found applicable, and the invention has for its object to provide, in a manner as hereinafter set forth, a 20 light and portable tent-like structure which when set up will constitute a bath house or dressing tent and when knocked down can be folded compactly and easily carried from 25 place to place, or which furthermore can be set up in a manner to provide a shade or sleeping tent, wind shield, and shooting blind or screen.

Further objects of the invention are to 30 provide, in a manner as hereinafter set forth, a portable cabinet of tent-like form, and which is simple in its construction and arrangement, strong, durable, conveniently set up and knocked down when occasion requires, thoroughly efficient in its use, and inexpensive to manufacture.

With the foregoing and other objects in view, the invention consists of the novel construction, combination and arrangement of 40 parts, as hereinafter more specifically described and illustrated in the accompanying drawings, wherein is shown an embodiment of the invention, but it is to be understood that changes, variations and modifications 45 can be resorted to which come within the scope of the claims hereunto appended.

In the drawings wherein like reference characters denote corresponding parts throughout the several views:—

50 Figure 1 is a perspective view showing the adaptation of a portable cabinet, in accordance with this invention, with the elements thereof arranged to provide a shade tent.

55 Figure 2 is a view similar to Figure 1, with the elements of the cabinet arranged to provide a sleeping tent.

Figure 3 is an elevation with the elements of the cabinet arranged to provide a bath house or dressing tent.

Figure 4 is a perspective view with the 60 elements of the cabinet arranged to provide a wind shield.

Figure 5 is a longitudinal sectional view of the cabinet with the elements thereof arranged to provide a bath house or dressing 65 tent.

Figure 6 is an inverted plan of the top of the bath house, or dressing tent.

Figure 7 is a rear elevation of the front 70 wall of the bath house or dressing tent.

Figure 8 is a fragmentary view in perspective, of a front post and top bars.

Figure 9 is a like view of the rear post and top bars.

Figure 10 is a perspective view of the 75 elements of the cabinet when folded.

Figure 11 is a fragmentary view in section of a modification.

A portable cabinet in accordance with this invention comprises an adjustable body portion, a top and a curtain.

The body portion includes a pair of front poles or standards 1, 2, and a pair of rear poles or standards 3, 4. Each of the standards is cylindrical, of substantial diameter 85 and height and has a tapered lower terminal portion 5, to facilitate the driving of a pole or standard into the ground for the purpose of securing it in an upright position. The poles or standards 1, 2, preferably are of 90 greater height than the poles or standards 3, 4, and by way of example the poles or standards 1, 2 are seven feet in length and the poles or standards 3, 4, are six and one-half feet in length, but it is to be understood 95 that the standards can be of any desired length.

Associated with the front and rear standards are four top bars, one of which is arranged at the front of the cabinet and is 100 termed a front bar and indicated at 6. Two of the bars are arranged at the sides of the cabinet and are termed side bars and are indicated at 7, 8; and the other of the bars is arranged at the rear of the cabinet and termed the rear bar and indicated at 9. The bar 6 is of less length than either of the bars 7, 8, but of greater length than the bar 9. The bars 7 and 8 are of greater length than either of the bars 6 or 9. 105 Each of the standards 1, 2, is provided near its upper end with a pair of sockets 110 and

11 disposed at right angles with respect to each other and each of the poles or standards 3, 4, at its upper end is provided with a pair of sockets 12, 13, disposed at right angles with respect to each other.

Each end of the bars 6, 7, 8 and 9 is provided with an adjustable coupling member which projects therefrom and is indicated at 14. Each of the coupling members 10 preferably consists of a metallic pin peripherally threaded, and which are screwed a substantial distance in the bar, as well as projecting a substantial distance therefrom. Preferably, the pin is screwed to the depth 15 of an inch in a bar and projects therefrom for a distance of about three-eighths of an inch, but it is to be understood that the coupling members can be secured in the bars as well as project therefrom for any desired 20 distance. Each coupling member has its outer end provided with a groove 15, to adjust the position thereof with respect to a bar.

When the bars 6 to 9 are set up relative 25 to the poles or standards 1 to 4, the coupling members of the bar 6 are extended into the sockets 11 of the poles or standards 1, 2. The coupling members at the forward ends of the bars 7 and 8 are extended into the 30 sockets 10 of the poles or standards 1, 2, and at the rear ends of the bars 7 and 8 are extended into the sockets 12 of the poles or standards 3, 4. The coupling members of the bar 9 are extended into the sockets 13 35 of the poles or standards 3 and 4. The bars 6, 7, 8 and 9 act to brace the poles or standards 1, 2, 3 and 4 and further provide means for stretching the side and back walls and top of the cabinet as well as maintaining 40 the cabinet in an extended position when set up. The front bar 6 provides means for suspending a curtain 16, employed for closing the front of the cabinet.

The side and back walls of the cabinet are 45 formed from a single body of suitable material, preferably canvas, and between the transverse center and one end of said body the latter has secured to its inner face, by rows of stitching 17, a strip of flexible material, which in connection with the body of material provides a pocket or loop 18. Secured to the body of material by rows of stitching 20, at a point between its transverse center and the other end thereof is a 50 strip of flexible material which provides a pocket 19. That part of the body of material which is arranged between the pockets 18 and 19 constitutes the back wall 21 of the cabinet. In lieu of setting up the pockets 55 or loops 18 and 19, in the manner as stated, the material is lapped as at 18' and secured together as at 19' to provide a pocket 20', see Figure 11. The body gradually increases in width from its back wall 21 towards each end.

The body of material which forms the side and back walls of the cabinet has each end thereof overlapped and secured by a row of stitching 22 to provide a pocket. The pocket at one end of the body of material, is indicated at 22 and that at the other end at 23. That portion of the body of material which is arranged between the pockets 18 and 22 constitutes one of the side walls of the cabinet, and said wall is indicated at 24. 70 That portion of the material between the pocket 19 and the pocket 23, constitutes the other side wall of the cabinet and which is indicated at 25.

Each of the pockets at its upper end is 80 provided with apertures 26, for the purpose of registering with the sockets at the upper ends of the posts or standards.

The standard 1 extends down through the pocket 22. The standard 3 extends down 85 through the pocket 18. The standard 4 extends down through the pocket 19, and the standard 2 extends down through the pocket 23. The diameter of the poles or standards with respect to the size of the pockets is such 90 as to provide a tight fit therebetween. The width of the back wall 21 is materially less than either of the side walls 24, 25.

The curtain 16, at its top, is provided with a pocket or loop 27 through which extends 95 the front bar 6. The curtain 16 has its inner face provided with a pair of oppositely disposed triangular flaps 28, 29 and each of said flaps has its outer edge secured by a row of stitching 30 to the curtain 16. Eyelets or grommets 30' are secured to the flaps 28 and 29 and to the curtain 16 at each lower corner of the latter. Fastener elements 31 are carried by the flaps 28 and 29 for detachably connecting the inner corners of the 100 flaps to the curtain 16. Flexible tie members 32 are arranged on the inner face of the curtain 16 and each of said tie members 32 has its upper end secured to the curtain 16. The curtain 16 forms the front wall of the 110 cabinet and is so set up with respect to the bar 6, that it can be shifted thereon, in a manner as shown in Figure 3. The flaps 28, 29, provide extension pieces for the front wall of the cabinet when the latter is used 115 as a sleeping tent. The curtain 16 is of greater height than the height of the cabinet to provide for the positioning of the curtain in the manner as shown in Figure 2 when the cabinet is set up as a sleeping tent.

The top, which is indicated at 34, and best shown in Figure 6, is formed from a body of flexible material, preferably canvas, and is reinforced at each side, as at 35, 36. The top 34 is tapering in contour and is provided 125 at a point inwardly of its front edge with a pair of eyelets or grommets 37, and at a point forwardly with respect to its rear edge with a pair of eyelets or grommets 38. Secured to the inner face of the top 34, at each 130

side thereof, by rows of stitching 39, is a flexible strip which provides a loop or pocket 40, and through said loops or pockets 40 extend the side bars 7 and 8. Flexible tie members 41 are secured to the inner face of the top 34. The top 34 is of greater width and of greater length than the body portion of the cabinet so that when the top 34 is set up relative to said body portion, the top 10 will overhang the upper ends of the front, sides and back of the body portion as indicated at 42, 43 and 44 respectively and act to close the upper end of said body portion.

When the poles or standards are set up 15 in a vertical position, the upper ends thereof extend through the eyelets 37 and 38, and mounted on each of the poles or standards 1, 2, below the top 34, is an eye 45 formed at the upper end of a guy rope 46 having its lower end anchored as at 47. Mounted upon each of the poles or standards 4, below the top 34 is an eye 48 formed 20 at each end of a flexible member 49, having extending therefrom a guy rope 50, which is anchored at its lower end, as at 51.

The rear bar 9 is connected to the standard 4, by a flexible member 52 so that when the bar 9 is not used it can be arranged in a pocket 53, as shown in Figure 4, which 30 is formed on the back 21.

When the cabinet is set up in the form of a sleeping tent as shown in Figure 2, securing elements 54 are attached to the eyelets 30' and anchored as at 55.

The back or rear wall 21 is provided 35 with receptacles or pockets 56 for storing any suitable articles, and the inner face of the side walls 24, 25, as well as the inner face of the rear or back wall 21 is provided 40 with garment hangers or supports 57. A tie member 58 is attached to the hangers 57 on the inner face of the side walls 24, 25. The pockets or receptacles 56 can be employed for holding toilet articles or jewelry, 45 and each of the pockets or receptacles preferably is reinforced at the top thereof. The garment hangers or supports 57 consist of horizontally and vertically disposed flexible straps. Each horizontally disposed strap is 50 secured at its ends, as at 59, and is supported by a vertical strap and with the latter secured at one end as at 60 to the wall, and at its other end as at 61 to the horizontally disposed strap centrally thereof.

The tie members 32, carried by the curtain 55 16, are employed for connection with the tie members 58 and also the tie members 62 carried by the side walls.

The guy rope 46, as well as the guy ropes 60 50 are not employed when the cabinet is set up as a bath house or dressing tent except when the wind is high. The guy ropes are further used when the curtain is hoisted or stretched out in front of the cabinet in the 65 manner as shown in Figure 1. The cabinet

can be used with or without the top, but the standards and bars are always employed. With the curtain or front wall in place the device will be set up as a dressing room for bathers on a beach, or can be used 70 as a shooting blind. If employed for a shooting blind the standards should be driven to such an extent that the lower edge of the canvas will be just above the ground. When the curtain is raised and stretched, the device will serve as a shade tent. When the standards are driven in the ground enough to position the bottom of the walls of the cabinet, on a level with the ground and the upper half of the curtain fastened and the lower end thereof stretched forwardly and further with the triangular flaps in place, the device can then be used as a sleeping tent. With the top removed and the front standards spaced wide apart, and further 75 with the guy ropes in place, the device can then be employed for a screen for wind and sun.

The manner of setting up the cabinet is 80 as follows:

Select the place on which the cabinet is to be set up, having due regard for the character of ground, direction of the wind and force. If there be no wind or only a 85 moderate breeze, the cabinet can be set up facing any direction, but should the wind be fresh the rear of the cabinet being narrow, should face the wind and be held by use of guy ropes. Lay the top 34 flat on the ground and stretch the four corners thereof taut, then make holes in the ground with tent pegs by driving them through the grommet in each corner of the top, after 90 which the latter is removed from the position placed in. One of the rear standards is then driven in one of the rear holes, the material from which the rear and side wall are set up is stretched the full width at the bottom thereof and the other rear standard 95 is then set up in a similar manner, after 100 which the bar 9 is connected to the two rear standards. If the wind is fresh then the guy rope 50 is positioned and said guy rope is fitted with a bridle. If the top of the cabinet has not been used as a pattern for 105 positioning the holes in the manner stated, then the front bar 6 is employed to set up a proper distance between the front standards. After the rear standards have been 110 mounted in position as stated, the side walls of the cabinet are stretched full length at the bottom thereof and then each front standard is driven in position and the side bars 7 and 8 connected with the front and rear standards. If the top 34 is to be 115 employed the side bars 7 and 8 are mounted in the pockets 40 and after which they are connected to the front and rear standards, but prior to the connecting of the side bars 120 to the front and rear standards, these latter 125

are inserted through the eyelets or grommets 37 and 38 in the top 34. After the side bars have been connected with the front and rear standards, the bar 6 is connected to 5 the front standards. When the top has been positioned in a manner as stated, it is fastened by the tie members 41, to the vertical straps of the garment hangers. When there is a very strong wind, the guy ropes 10 46 are employed to steady the front standards.

The cabinet is now ready for use and the front wall or curtain 16 can be permanently fastened on one side, after which it can be 15 drawn across the front of the cabinet and fastened on the opposite side. The standards fit tightly and will not become loose and when the top is in the position as stated, it provides for absolute security. Security 20 can also be obtained without the top by placing the ring 45 of the guy rope which is connected to the farthest front standard, then extend the guy rope around the other front standard and connect the rope to a tent peg, and this prevents the two front standards from spreading.

When dismantling the cabinet, the guy ropes are disconnected, if used, the top removed, side bars disconnected, after which 30 the rear bar is removed and then the curtain is disconnected and the standards pulled up. After the standards have been pulled up, the two rear standards are positioned alongside each other and the curtain and top rolled up 35 separately and placed alongside the two rear poles. The flexible body portion is then rolled up in a compact bundle and which incloses the curtain and top and after the several elements are rolled up in the manner 40 as stated, the bundle is lashed with guy ropes.

It is thought that the many advantages 45 of a portable cabinet which provides a bath house or dressing tent, a sun and wind shield, a beach awning, a shooting blind and a sleeping tent, can be readily understood from the foregoing description taken in connection with the accompanying drawings, particularly in view of the fact that the device 50 has originality of shape, simplicity and cheapness of construction, combining minimum size and weight with maximum room and convenience, and furthermore in its originality of construction in having standards 55 and bars connected to the canvas to prevent warping. The height of the canvas is adjustable, providing a simple and convenient way for ventilating the cabinet by leaving space at the top and bottom thereof and 60 furthermore whereby the top and body of the cabinet are separate, and although the preferred embodiment of the invention is as illustrated and described, yet changes in the

details of construction can be had which will fall within the scope of the invention as 65 claimed.

What we claim is:—

1. A portable cabinet comprising a flexible member of substantial length and width provided at each end with a transversely extended pocket and further provided at a point between its transverse center and each end with a transversely extending pocket, a standard extending through each of said pockets and projecting above and below the 75 same, brace bars interposed between the standards at the top thereof and provided with coupling members detachably engaging in said standards, a top member having said standards extending therethrough and provided with means for receiving certain of said brace bars, a front member shiftably mounted on and suspended from the brace bar between the standards carried by said end pockets and provided on its inner face 80 with triangular shaped flaps constituting extensions, said flaps secured at their outer side edges to said front member and having the inner sides detachably connected to said member, and guy ropes connected to the 85 standards secured to the end pockets and providing means for maintaining said front member at an inclination with respect to said standards.

2. A knock-down portable cabinet comprising a pair of spaced rear standards, a pair of spaced front standards spaced from the rear standards, a vertically disposed flexible member positioned against said pairs of standards and connected at its ends to said 90 front standards and intermediate its ends to said rear standards, a top member mounted on said standards and overlapping said flexible member, brace bars interposed between said standards and having connecting 95 members detachably engaging with the standards, a front member depending from and slidably mounted on the brace bar between the front standards, and supporting elements connected to the inner face of said 100 flexible member.

3. In a portable cabinet for the purpose set forth a collapsible rectangular body portion including an outwardly shiftable front wall, said wall having secured to its 115 inner face at each side of the lower portion thereof a pair of oppositely disposed triangular shaped members adapted to extend inwardly at right angles to said wall when the latter is shifted outwardly, and a removable top for the body portion.

In testimony whereof, we affix our signatures hereto.

JOHNSTONE H. QUINAN.
JEPTHA V. HARRIS.
